OPEN TOP DISPLAY CASE WITH SLIDABLE HOOD

Joseph R. Pichler, Dayton, Ohio, assignor to General Motors Corporation, Dayton, Ohio, a corporation of Delaware

Application February 23, 1952, Serial No. 272,997

11 Claims. (Cl. 62—89.5)

1

This invention relates to refrigerated display cases of the self-service type.

In the past, self-service refrigerated display cases or cabinets have usually been arranged in retail stores with their backs against a wall of the building in which the store is located. Replenishing or reloading stock into a cabinet in such an arrangement of a display case obstructs the customer's view of the contents of the case, at the front thereof, and the crates, boxes and/or baskets containing a supply of food products to be reloaded into the case during a reloading operation are ordinarily placed in the path of customers passing by a case and thereby interfere with the customers serving themselves from the self-service case. Owners of supermarkets and the like have realized this inconvenience to their customers and many now arrange or have arranged display cases in rows and provide a customers' aisle in front of the cases and a relatively narrow supply aisle in back of the cases where the attendants must place crates, baskets and/or boxes containing the food products to be loaded into the display cases. The back portion of the open top of self-service display cases and particularly those maintained at a temperature below freezing is ordinarily covered with a stationary hood for the purpose of protecting the interior thereof against drafts in the room so as to insure proper circulation of cold air in the case. This hood renders it difficult, if not impossible, to reload a case from its back side and thus the attendant is required to walk around the case into the path of customers at the front thereof, in the customers' aisle, to place additional stock in the case. Such is not at all impressive or pleasing to customers, and the latter arrangement of display cases has not been entirely satisfactory. It therefore becomes highly desirable and important to provide for the restocking or reloading of substantially open top display cases from the rear side thereof so that movements of the attendant will not interfere with or inconvenience customers serving themselves at the front of a case.

An object of my invention is to provide an improved substantially open top type refrigerated self-service display case.

Another object of my invention is to render a hood employed to cover a rear portion of the open top of a display case movable so as to increase the utility of the case and facilitate the reloading thereof with food products.

A further object of my invention is to provide a substantially open top refrigerated display case

2

with flat end walls, the tops of which terminate in substantially the same horizontal plane, to movably support a hood thereon for covering a portion of the open top of the case and which hood is movable toward the front wall of the case so as to permit loading of the case from the rear side thereof.

A still further object of my invention is to provide a hood structure on a refrigerated display case to normally cover the back portion of a substantially open top of a compartment in the case and which hood structure is movable to a position intermediate front and rear walls of the case to open the normally covered back portion of the compartment to permit reloading of the compartment from its rear side and to proportion the hood structure relative to the distance between front and rear walls of the case so that when the hood structure is so moved the front portion 20 of the open top compartment is left open to also provide access to the interior thereof from the front side of the case.

In carrying out the foregoing objects, it is a more specific object of my invention to provide 25 a hood over a portion of the open top of a refrigerated display case, which hood is rollable along flat end walls of the case and carries roller means engageable with a side of the end walls of the case to guide the hood during movement thereof.

Further objects and advantages of the present invention will be apparent from the following description, reference being had to the accompanying drawings wherein a preferred form of 30 the invention is clearly shown.

In the drawings:

Figure 1 is a perspective view of a substantially open top self-service display case having my invention embodied therein;

Figure 2 is an enlarged vertical sectional view taken on the line 2—2 of Figure 1 showing a movable hood on the case in a position to cover a rear portion of the open top thereof;

Figure 3 is a fragmentary sectional view similar to Figure 2 and shows the hood on the open top case moved in a direction toward the front wall thereof;

Figure 4 is a top view of the display case on a smaller scale with the hood thereon shown in the position thereof disclosed in Figure 3;

Figure 5 is an enlarged fragmentary sectional view taken on the line 5—5 of Figure 2 showing roller means on the hood engaging a side of the upright end walls of the display case;

Figure 6 is an enlarged fragmentary sectional

view taken on the line 6—6 of Figure 2 showing a roller on the hood resting upon and rollable along the flat topped case end walls; and,

Figure 7 is an enlarged fragmentary sectional view taken on the line 7—7 of Figure 2 showing a skid depending from the hood and engaging the top of a wall of the case.

My invention is particularly applicable to a substantially open top refrigerated display case of the type fully illustrated and described in detail in the copending application of Marshall W. Baker, Serial No. 193,795, filed November 3, 1950, Patent No. 2,661,604, dated December 8, 1953, and assigned to the assignee of the present application.

Referring to the drawings, for illustrating my invention, I show in Figure 1 thereof of a substantially open top self-service display case, generally represented by the reference character 10, comprising a cabinet provided with a bottom wall 11, a long rear wall 12, a long front wall 14, and end walls 16 and 17. These cabinet walls are all formed of or comprise inner and outer sheet metal panels or shells, as is conventional in the art, and have any suitable or desirable insulating material 18 disposed therebetween. The upper part of front wall 14 is formed by a suitable or conventional multiple glass pane structure 19 which extends from one end 16 to the other end wall 17 of case 10 to provide a window through which foods or packaged frozen food products on display in the case may be viewed. The tops of all the upright walls or at least the tops of end walls 16 and 17 of case 10 are continuously flat and terminate in substantially the same horizontal plane. The cabinet walls 11, 12, 14, 16 and 17 form an elongated open top compartment in the display case 10. A unitary cover structure or hood, generally represented by the reference character 20, extends continuously throughout the length of case 10 and projects a short distance from the rear cabinet wall 12 to normally cover the back portion of the open top compartment therein. This hood 20 is supported upon an inverted U-shaped metal cap 21 disposed over the flat top of at least the cabinet end walls 16 and 17 and is movable therealong in a direction transverse to the length of the display case 10 or toward the front wall 14 thereof for a purpose to be hereinafter described.

The interior of the substantially open top compartment in display case 10 may be divided into an upper chamber 24 and a lower chamber 26 in any suitable or conventional manner and preferably by a sheet metal member 27 as is disclosed in the M. W. Baker application hereinbefore referred to. A food supporting device or structure, generally represented by the reference character 29, is inset within case 10 and is located in the upper chamber 24 of the display case compartment. Food supporting device 29 may be of any suitable or conventional construction and preferably cooperates with member 27 to provide air passages, ducts and/or flues for the circulation of air from upper chamber 24 to the lower chamber 26, through the ducts or flues and over foods products stored in or on the device 29 as is shown and described more in detail in said M. W. Baker application. It is to be noted that all portions of the food supporting device 29 are disposed below the tops of upright walls of display case 10. A plurality of blowers or fans 31, driven by electric motors 32, are spaced apart along the length of case 10 adjacent to an evaporator 33 of a closed refrigerating system associated

with the display case 10. This evaporator 33 and the blowers or fans 31 are located in the lower chamber 26 of case 10. Air in the case 10 is cooled, preferably well below 32° F., and the blowers or fans 31 serve as means for circulating air over evaporator 33 where it is cooled and caused to flow through the various passages, ducts, and/or flues onto and over food products stored in or on the device 29.

The cover or hood structure 20 comprises a metal piece 36 stamped and formed to provide the top, side and end walls thereof (see Figures 5 and 6). A metal plate 37 is secured to piece 36 to form the bottom wall of hood 20. Any desirable or conventional insulating material 38 may be disposed between the metal piece 36 and plate 37 to suitably insulate the hood 20. The bottom wall or plate 37 has its undersurface preferably made reflective by coating or painting a reflecting material thereon. This reflective undersurface of hood structure 20 tends to deflect cold air contacting the same and thereby lessens the transference of cold air through the hood. Buttons or the like skids 39 (see Figure 7) are secured in any suitable manner, such as by C-shaped washers, to the bottom plate 37 of hood 20 at each of the rear corners thereof and engage the top cap 21 on the walls 16 and 17 of case 10 to aid in supporting the hood thereon. To each of the forward corners of hood 20 I secure, by suitable screws or the like (see Figure 6), a bracket 41 to plate 37 which bracket carries a roller 42 mounted on a horizontal shaft 43 riveted or otherwise rigidly attached to bracket 41. Rollers 42 and their carrying brackets are inset into hood structure 20 from the lower side thereof so as to depend from the bottom plate 37 substantially the same distance that the skids 39 depend therefrom. The skids 39 and rollers 42 support hood 20 in slightly spaced relation from the top cap 21 of walls 12, 16, and 17 of case 10 to eliminate friction between these walls when the hood is moved relative thereto for a purpose to be presently described. In order to guide the hood 20 during movement thereof along the cap 21 on its supporting walls 16 and 17 of case 10, I mount a pair of spaced apart brackets 46, by suitable screws or the like, to the underside of plate 37 at both ends of the hood and secure a roller 47 to each of the pair of brackets 46 by a vertical stud or shaft 48 riveted or otherwise rigidly attached to the brackets 46 (see Figure 5). I also provide means on hood 20 to prevent movement of its back edge rearwardly beyond the rear wall 12 of cabinet or case 10. This means in the present disclosure comprises a pair of spaced apart substantially L-shaped bracket members 49 (see Figures 5 and 6) secured to the bottom plate 37 of hood 20 by suitable screws or the like. The depending portion of the L-shaped brackets 49 extends below the top of rear wall 12 of the case 10 and form stops engageable with the inner side of wall 12 when the hood is moved to its normal back position. It is to be noted that the two rollers 42 are rollable along the metal caps 21 on the flat top walls 16 and 17 of case 10 and that the four rollers 47 form roller means engageable with the inner surface of these walls to provide guides for the hood 20. It is well known that objects constructed of poly-amine material or polymeric amides having a protein-like chemical structure may be moved along or rolled upon metal surfaces with much less friction than moving metal members upon or against one another and therefore I prefer to

form the skids 39 and rollers 42 and 47 of such or similar material.

When it becomes necessary to replenish the food supporting device 29 in the open top compartment of the self-service refrigerated display case herein disclosed with food products, the attendant will place crates, boxes or baskets containing the products in the stocking or supplying aisle in back of the display case where it will not interfere with customers passing in front of the case along the customers' aisle. The attendant will then move the hood structure 20 transversely of the display case 10 and toward the front wall 14 thereof to open the rear portion of the elongated substantially open top food compartment normally covered by the hood. During this movement of hood 20, its rollers 42 roll upon the cap 21 at the top of flat topped walls 16 and 17, its skids 39 slide therealong and the rollers 41 bear against and roll along the inner surface of walls 16 and 17 to guide and prevent binding of the hood during its movement. The hood 20 is moved forwardly upon case 10 preferably to a position part way between the rear wall 12 and front wall 14 thereof whereby a front portion of the open top compartment in the case, between the front of hood 20 and the front wall 14, remains uncovered (see Figures 3 and 4). The uncovered front portion of the open top of the case permits customers to serve themselves while the attendant is restocking food products into or upon the device 29 over the rear wall 12 of the case and from in back of the same. After the attendant has refilled the display case 10, its hood 20 is moved rearwardly thereon back into its normal position shown in Figures 1 and 2 of the drawings to cover that portion of the open top compartment in the display case for the purpose of protecting and insuring the correct or desired air circulation originally established in the case.

From the foregoing, it should be apparent that I have provided an improvement in refrigerated display cases which overcomes certain difficulties in the use thereof particularly in busy and crowded supermarkets and the like where it frequently becomes necessary to reload a case during shopping hours. By providing an elongated display case with a hood movable transversely thereof, as herein described, attendants may reload the case over the cabinet rear wall from a point in back of the cabinet. This eliminates the possibility of movements of an attendant inconveniencing or molesting customers attempting to serve themselves from the display case. It also avoids the necessity of placing crates, boxes and baskets, employed by the attendant during the act of restocking of the case, in the path of customers or carts being pushed by them at the front of the case.

While the form of embodiment of the invention as herein disclosed constitutes a preferred form, it is to be understood that other forms might be adopted as may come within the scope of the claims which follow.

What is claimed is as follows:

1. A self-service refrigerated display case comprising in combination, a bottom wall, a rear wall, a front wall and end walls forming an elongated open top compartment in said case, a food supporting device inset within said compartment, means for cooling air in said case, means for circulating the cooled air over food products on said device, an insulated unitary hood structure on said case extending continuously throughout

the length thereof with its ends engaging and supported by said end walls, said hood structure projecting from said rear wall to normally cover the back portion of the open top of said elongated compartment between said front and rear walls, and said hood structure being movable along said end walls in a direction toward said front wall to open the normally covered portion of said compartment open top and provide access to said food supporting device over said rear wall from in back of said case.

2. A self-service refrigerated display case comprising in combination, a bottom wall, a rear wall, a front wall and end walls forming an elongated open top compartment in said case, a food supporting device inset within said compartment, means for cooling air in said case, means for circulating the cooled air over food products on said device, an insulated unitary hood structure on said case extending continuously throughout the length thereof with its ends engaging and supported by said end walls, said hood structure projecting from said rear wall to normally cover the back portion of the open top of said elongated compartment between said front and rear walls, and said hood structure being movable along said end walls in a direction toward said front wall to open the normally covered portion of said compartment open top and permit access to said food supporting device over said rear wall from in back of said case, and means for guiding said hood structure during movement thereof.

3. A self-service refrigerated display case comprising in combination, a bottom wall, a rear wall, a front wall and end walls forming an elongated open top compartment in said case, the top of said end walls being flat and terminating in substantially the same horizontal plane, a food supporting device inset within said case and having all portions thereof disposed below the top of upright walls of said compartment, means for cooling air in said case, means for circulating the cooled air over food products on said device, a rigid hood projecting from said rear wall and extending continuously throughout the length of said elongated compartment to normally cover the back portion of said open top thereof between said front and rear walls, and said rigid hood being supported by and movable along said flat end walls in a direction toward said front wall to open the normally covered portion of said compartment open top.

4. A self-service refrigerated display case comprising in combination, a bottom wall, a rear wall, a front wall and end walls forming an elongated open top compartment in said case, the top of said end walls being flat and terminating in substantially the same horizontal plane, a food supporting device inset within said case and having all portions thereof disposed below the top of upright walls of said compartment, means for cooling air in said case, means for circulating the cooled air over food products on said device, a rigid hood projecting from said rear wall and extending continuously throughout the length of said elongated compartment to normally cover the back portion of said open top thereof between said front and rear walls, said rigid hood being supported by and movable along said flat end walls in a direction toward said front wall to open the normally covered portion of said compartment open top, and means on said hood engaging an inner part of the end walls of said case to guide the same during movement thereof.

7

5. A self-service refrigerated display case comprising in combination, a bottom wall, a rear wall, a front wall and end walls forming an elongated open top compartment in said case, the top of said end walls being flat and terminating in substantially the same horizontal plane, a food supporting device inset within said case and having all portions thereof disposed below the top of upright walls of said compartment, means for cooling air in said case, means for circulating the cooled air over food products on said device, a rigid hood projecting from said rear wall and extending continuously throughout the length of said elongated compartment to normally cover the back portion of said open top thereof between said front and rear walls, said rigid hood being movable along said flat end walls in a direction toward said front wall to open the normally covered portion of said compartment open top, said hood having rollers engaging and being rollable upon said flat top of said end walls, and said hood also having roller means depending therefrom and engaging a side of said end walls to guide the same during movement thereof.

6. A self-service refrigerated display case comprising in combination, a bottom wall, a rear wall, a front wall and end walls forming an elongated open top compartment in said case, the top of said end walls and the top of at least said rear wall being flat and terminating in substantially the same horizontal plane, a food supporting device inset within said case and having all portions thereof disposed below the top of upright walls of said compartment, means for cooling air in said case, means for circulating the cooled air over food products on said device, a rigid hood on said case extending continuously throughout the length of said elongated compartment, said rigid hood overlying said rear wall and projecting therefrom to normally cover the back portion of said compartment open top between said front and rear walls, and said hood being supported by and movable along said flat end walls in a direction toward said front wall to open the normally covered portion of said compartment open top.

7. A self-service refrigerated display case comprising in combination, a bottom wall, a rear wall, a front wall and end walls forming an elongated open top compartment in said case, the top of said end walls and the top of at least said rear wall being flat and terminating in substantially the same horizontal plane, a food supporting device inset within said case and having all portions thereof disposed below the top of upright walls of said compartment, means for cooling air in said case, means for circulating the cooled air over food products on said device, a rigid hood on said case extending continuously throughout the length of said elongated compartment, said rigid hood overlying said rear wall and projecting therefrom to normally cover the back portion of said compartment open top between said front and rear walls, said hood being supported by and movable along said flat end walls in a direction toward said front wall to open the normally covered portion of said compartment open top, and means on said hood engaging a part of the end walls of said case to guide the same during movement thereof.

8. A self-service refrigerated display case comprising in combination, a bottom wall, a rear wall, a front wall and end walls forming an elongated open top compartment in said case, the top of said end walls and the top of at least said

5 rear wall being flat and terminating in substantially the same horizontal plane, a food supporting device inset within said case and having all portions thereof disposed below the top of upright walls of said compartment, means for cooling air in said case, means for circulating the cooled air over food products on said device, a rigid hood on said case extending continuously throughout the length of said elongated compartment, said rigid hood overlying said rear wall and projecting therefrom to normally cover the back portion of said compartment open top between said front and rear walls, said hood being movable along said flat end walls in a direction toward said front wall to open the normally covered portion of said compartment open top, said hood having rollers engaging and being rollable upon said flat top of said end walls, and said hood also having roller means depending therefrom and engaging a side of said end walls to guide the same during movement thereof.

9. A self-service refrigerated display case comprising in combination, a bottom wall, a rear wall, a front wall and end walls forming an elongated open top compartment in said case, the top of said end walls and the top of at least said rear wall being flat and terminating in substantially the same horizontal plane, a food supporting device inset within said case and having all portions thereof disposed below the top of upright walls of said compartment, means for cooling air in said case, means for circulating the cooled air over food products on said device, a rigid hood on said case extending continuously throughout the length of said elongated compartment, said rigid hood overlying said rear wall and projecting therefrom to normally cover the back portion of said compartment open top between said front and rear walls, said hood being movable along said flat end walls in a direction toward said front wall to open the normally covered portion of said compartment open top, said hood having rollers engaging and being rollable upon said flat top of said end walls, and said hood also having roller means depending therefrom and engaging a side of said end walls to guide the same during movement thereof, and stop means on said hood preventing movement thereof rearwardly of said case beyond said rear wall.

10. A self-service refrigerated display case comprising in combination, a bottom wall, a rear wall, a front wall and end walls forming an elongated open top compartment in said case, a food supporting device inset within said compartment, means for cooling air in said case, means for circulating the cooled air over food products on said device, an insulated unitary hood structure on said case extending continuously throughout the length thereof with its ends engaging and supported by said end walls, said hood structure projecting from said rear wall to normally cover the back portion of the open top of said elongated compartment, said hood structure being movable along said end walls in a direction transverse to the length of said case to a point intermediate said front and rear walls to open the normally covered portion of the open top of said compartment to provide access to said food supporting device over said rear wall from in back of said case, and the width of said hood structure relative to the distance between said front and said rear walls being such that when said hood structure is so moved the front portion of the open top of said compartment remains open

for access to said device over said front wall from in front of said case.

11. A self-service refrigerated display case comprising in combination, a bottom wall, a long upright side wall, another long upright side wall and relatively short end walls providing an elongated open top compartment in said case, a food supporting device inset within said compartment, means for cooling air in said case, means for circulating the cooled air over food products on said device, a rigid hood structure on said case extending continuously throughout the length thereof with its ends engaging and supported by said end walls, said hood structure projecting from one of said long side walls over and normally forming a cover for that portion of the open top

10

of said elongated compartment adjacent said one long side wall, and said hood structure being movable along said end walls in a direction away from said one long side wall toward the other of said long side walls to open the normally covered portion of said compartment open top and permit access to said food supporting device over said one long side wall.
